(57) **CLAIM**

The ornamental design for a support for test device, as shown and described.

DESCRIPTION

FIG. 1 is a front right perspective view of a support for test device showing our new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom view thereof.

The broken lines of short length shown in the drawings illustrate portions of the support for test device that form no part of the claimed design. The broken lines of long length define the boundaries of the claimed design.
